RUSSELL R. SAMUELS, OF CHICAGO, ILLINOIS, ASSIGNOR TO THE AMERICAN LAUNDRY MACHINERY COMPANY, OF CINCINNATI, OHIO, A CORPORATION OF OHIO

APRON TENSION DEVICE

Application filed December 3, 1930. Serial No. 499,700.

My invention relates to an apron tension device and, particularly, to an apron tension device that may be applied in flat work ironers in which one or more padded rolls 5 operate with heated chests and in which suitable aprons are employed to guide the work to be pressed into and out of the machine, the aprons passing below the chest or chests for a greater portion of their length.

10 In flat work ironers of the above type, the tension on the wide endless aprons that are usually of canvas and pass for a greater portion of their length below the heated chest or chests must be relieved at the end of a day's run or operation of the ironing machine or during the time when the machine is not in operation. During this shut-down period the aprons which are normally damp from contact with wet goods become dry and considerably shorter due to shrinkage, the result being that when tension is again applied to the aprons on beginning the operation of the machine, which tension is made by apparatus normally set to adjust the tension of the aprons to a high and low point, the tension is too great causing more or less trouble aside from damaging the aprons and producing unsatisfactory results. Heretofore, to avoid this inconvenience, the machine operator would slightly reduce the tension on the aprons by turning the adjusting screws whereupon, after the machine has been in operation for some time and the aprons consequently become heated and stretched, they are too loose. Then, the operator must again resort to the adjusting screws to secure the proper tension on the aprons. Since this re-adjustment of the screws and apron required the time of one who is more or less expert in apron adjustment, the operation of the machine was necessarily delayed, it being impracticable to have each machine operator more or less expert in apron adjustment.

15 The objects of my invention are to provide a means for automatically adjusting the apron tension thereby obviating the necessity of adjusting the apron tension by manually operated means at or after each operation of the machine; to prevent a ridge or fold forming at any point in the apron; and to provide

flexible or yielding tension on the aprons which will compensate for shrinkage or stretch thereof.

Various other objects and advantageous features of my invention will be seen in the following description and one embodiment thereof may be seen in the accompanying drawings wherein similar characters of reference designate corresponding parts, and wherein:

Fig. 1 is a longitudinal sectional view of an ironing machine embodying my invention; and Fig. 2 is an enlarged detail view of the apron tension adjusting means apart from the ironing machine.

Referring to the drawings, I have shown an ironing machine of the usual type consisting of four padded rolls 1 mounted above four chests 2 in such manner as to contact with the upper concave surfaces of the chests and the rolls and chests being supported on a suitable frame 3. The padded rolls 1 are rotatably mounted in side frames 4 which are vertically adjusted and guided in suitable ways. To move the frames 4, suitable links 5 are connected to the opposing ends of the frames, the links having their lower ends connected to eccentrics 6 mounted on shafts 7 which are rotated in unison by means of a worm shaft 7' that may, in turn, be rotated either manually or by power means. With this construction, it will be seen that rotation of the shafts 7 will cause raising or lowering of the frames 4 and raising or lowering of the rolls 1 out of or into contact with the chests 2.

In accordance with my invention, a means is provided for adjusting the tension of endless aprons 8 and 8' that provide a means for delivering the work ironed from the machine and pass beneath the chests 2 for the greater portion of their length. This means consists of two triangular frames 9 mounted at each side of the delivery end of the machine and being pivoted as at 10 to the main frame 3. The two corners of the frames 9 remote from the pivots 10 are provided with similar pairs of parallel shafts that radiate substantially from the lowermost point of the triangular frame. Such pairs of shafts and their asso-

ciated parts are duplicates and hence only one such set will be described.

One of the shafts designated by the numeral 11 is plain or smooth and rigidly

- 5 mounted at each end of the frame 9 as shown in Fig. 2 while the shaft 12 forming the other shaft of one pair is threaded and rotatably mounted at each end of the frame 9 and is provided with a means consisting of a crank 10 13 whereby the shaft may be rotated. Two blocks are mounted to travel on the shafts 11 and 12, one block 14 being free to slide on both shafts and the other block 15 being free to slide on the shaft 11 but having a threaded opening therein through which the shaft 12 fits, the shaft 12 being provided with threads 16 for cooperating with the threads in the block 15 to move the block one way or the other depending on the direction of rotation 20 of the shaft 12. The block 14 is spaced a short distance from the block 15 and coiled expanding springs 17 are interposed between the two blocks, one spring encircling each of the shafts 11 and 12.

- 25 As shown in the drawings, two of the blocks 14 arranged on opposite sides of the machine support a shaft roller 18 and the other set of blocks 14 support a shaft roller 19. The roller 18 is an idler over which the upper lap of the delivery apron 8 travels and the roller 19 is an idler over which the delivery apron 8' travels.

- Delivery apron 8 passes from the roller 18 down about the rear rounded end of the rearwardmost chest 2, thence forward against the lower sides of all four chests 2, thence about the live or driven roller 20, thence rearwardly under idler rollers 21 and 22, thence on an incline upwardly about an idler roller 23 and thence forwardly again over the idler roller 18. The apron 8' passes from the roller 19 on a decline and under an idler roller 24, thence forwardly under idler rollers 25 and 26, thence upwardly about a live or driven roller 27, thence downwardly on the apron 8 and about the live or driven roller 20, and thence rearwardly with the apron 8 below the idler rollers 21 and 22 and thence on an incline rearwardly to and around idler roller 19. Thus, it will be seen that the aprons 8 and 8' travel parallel to and in contact with each other for substantially the combined length of the chests 2.

- 55 To provide a means for increasing or decreasing the tension on the endless aprons 8 and 8', one of the shafts 7 at the delivery end of the machine has two large cams 28 rigidly mounted thereon to rotate therewith which cooperate with the rollers 29 mounted on the triangular frames 9 that are pivoted as at 10 on the main frame 3. With this construction, it will be seen that when the shafts 7 are rotated to raise or lower the frames 4 and rolls 1 supported thereby, the frames 9 will be correspondingly raised or

lowered to increase or reduce the tension on the endless aprons 8 and 8'. However, it will be noted that the high point of the cams 28 which, when in contact with the rollers 29, causes the frames 9 to be in their uppermost position with the endless aprons 8 and 8' under tension is directly opposite to the high points on the eccentrics 6 which, when in their uppermost position cause the rolls 1 to be raised away from the chests 2. In other words, the high points of the cams and eccentrics are directly opposite each other relative to the shafts 7. Thus, when the rolls 1 are in engagement with the chests 2 as shown in Fig. 1, the frames 9 will be in their raised position to place the aprons 8 and 8' under tension. In a like manner, when the eccentrics 6 are in such position as to raise the rolls 1 from the chests 2, the rollers 29 are in contact with the lower points of the cams 28 which will permit the frames 9 to lower and relieve the tension on the endless aprons 8 and 8'.

90 In the operation of this device, when the machine is first set for operation, the frames 9 are moved to their uppermost position as shown in Fig. 1 by rotating the shafts 7 to bring the rolls 1 into engagement with the chests 2 at which time the screw shafts 12 are turned to secure the proper tension on the aprons. After such desired tension is obtained, the machine is operated through a period of time which may be a day's "run" and then the tension on the aprons is relieved in the manner hereinbefore described simultaneously with movement of the rolls out of engagement with the chest. Also, as hereinbefore stated, when tension is again placed on the aprons prior to operation of the machine, the aprons are considerably shorter because of shrinkage thereof in drying but the shortened condition of the aprons is compensated for by further compression of the springs 17, the springs having been somewhat compressed in turning the shaft 12 to obtain the proper first tension on the endless aprons. In a like manner, as the machine has been operated, the aprons become heated and moist which causes them to stretch as hereinbefore described and such stretching of the aprons in no way interrupts the operation of the machine because the springs 17 will again exert the proper tension on the aprons by moving the blocks 14 and idler rollers carried thereby upwardly to take up any stretch of the aprons. It will be understood that the springs 17 are of sufficient length and strength to at all times compensate for the greatest amount of shrinkage or stretch that will take place in the aprons and that the length of springs and the shafts on which they are mounted may be various in length of aprons used.

100 105 110 115 120 125 130 Referring to the drawings and the preceding description, it will be seen that I have

provided a device embodying numerous novel and advantageous features. One of these features resides in the fact that the endless aprons may be adjusted to obtain the proper tension thereon prior to the beginning operation of the machine and need not hereafter be adjusted since any slack due to stretch or any shrinkage will be compensated for by the resilient means provided. Another feature resides in the fact that means have been provided for automatically increasing or decreasing the tension on the aprons in synchronism with the movement of the ironing rolls into or out of engagement with the ironing 5 chests which movement is caused to take place prior to the beginning of and at the end of a day's run or ironing operation. It will be readily apparent that such combination of features is highly advantageous and desireable and will eliminate in a large measure if not entirely the necessity of manual adjustment after the ironing operation has been started by the manipulation of various adjustment screws manually and the wear and 10 injury to endless aprons due to the beginning of an ironing operation while the aprons are in a shrunk condition and too tight on the rolls around which they travel. As in most ironing machines, the goods ironed is delivered onto the endless apron 8 and passes between such aprons and lower side of the ironing chest to a position between the endless aprons 8 and 8' and is thus carried between such aprons to the point of delivery.

35. What I claim is:

1. An ironing machine comprising a frame, ironing members carried by said frame including ironing chests and ironing rolls, means for moving said rolls into and out of ironing relation with said chests, a delivery apron, a movable bracket having rollers thereon about which said apron travels, said bracket being movable to release position for relieving the tension of said apron and movable into position to bring said apron into operative relation with said ironing members, means carried by said bracket for adjusting the tension of said apron including two blocks one of which is freely movable relative to the other and is provided with one of said rollers about which said apron passes, resilient means interposed between said blocks tending to move said freely moving block away from said other block, and positive means for moving said other block to vary the force exerted on said freely moving block by said resilient means, said resilient means being effective to permit movement of said freely moving block to vary the tension in said apron automatically in accordance with contraction and expansion of the apron.

2. An ironing machine comprising a frame, ironing members carried by said frame including ironing chests and ironing rolls, means for moving said rolls into and out of

ironing relation with said chests, a delivery apron, a movable bracket having rollers thereon about which said apron travels, said bracket being movable to release position for relieving the tension of said apron and movable into position to bring said apron into operative relation with said ironing members, means for moving said bracket in synchronism with the movement of said ironing rolls, means carried by said bracket for adjusting the tension of said apron including two blocks one of which is freely movable relative to the other and is provided with one of said rollers about which said apron passes, resilient means interposed between said blocks tending to move said freely moving block away from said other block, and positive means for moving said other block to vary the force exerted on said freely moving block by said resilient means, said resilient means being effective to permit movement of said freely moving block to vary the tension in said apron automatically in accordance with contraction and expansion of the apron.

In testimony whereof I hereby affix my signature.

RUSSELL R. SAMUELS.
